The ornamental design for a wrap around brake light, as shown and described.

DESCRIPTION

FIG. 1 is a top, front perspective view of a wrap around brake light showing my new design;
FIG. 2 is a side elevational view thereof as seen from the left of FIG. 1;
FIG. 3 is a front elevational view thereof; and,
FIG. 4 is a top plan view thereof, the bottom being a mirror image.
The rear and the side seen from the right of FIG. 1 are affixed to a vehicle and therefore hidden in use.
